UNITED STATES PATENT OFFICE.

HENRY VAN HOEVENBERGH, OF NEW YORK, N. Y., ASSIGNOR TO NOAH C. ROGERS, OF SAME PLACE.

ELECTRIC LOCOMOTION.

SPECIFICATION forming part of Letters Patent No. 607,302, dated July 12, 1898.

Application filed November 20, 1896. Serial No. 612,803. (No model.)

To all whom it may concern:

Be it known that I, HENRY VAN HOEVENBERGH, a citizen of the United States, and a resident of the city of New York, in the county 5 and State of New York, have invented certain new and useful Improvements in Electric Locomotion, of which the following is a specification.

This invention relates to the propulsion of 10 electrically-operated vehicles, the object being to permit vehicles provided with propelling electric motors to traverse an ordinary roadway not provided with tracks or rails or other paraphernalia on the surface such as 15 is commonly employed in electric locomotion.

In carrying out the invention I provide two elevated or aerial supply-conductors extending along the roadway to furnish a path for the outgoing and return current from a stationary generator or dynamo-electric machine 20 located at any suitable point of supply and provide each vehicle with a trolley or current-collector of novel construction which makes a continuous contact with the supply-conductors and leads the current to and from the electric motor carried by each vehicle. Thus 25 the current is led to and from the motor by an independent insulated conductor connecting with the generator and all earth contacts or paths for the current are dispensed with. 30 Each trolley is provided with rolling collectors in firm mechanical engagement with one supply-conductor and a light yielding insulated collector held in elastic engagement 35 with the other supply-conductor, and trolleys moving in definite directions are held in mechanical engagement with opposite supply-conductors. Guide-rails are provided on the trolley-frames to properly fold back the elastic 40 contact of a trolley passing in the opposite direction and thus permit it to pass.

The invention comprises a trolley engaging two guiding-conductors adapted to withdraw one of its contacts in passing a trolley 45 moving in the opposite direction.

It comprises also a trolley mechanically guided by one conductor and having a separable elastic connection with the other conductor capable of being withdrawn to permit 50 another trolley to pass.

It comprises also specific features of the

trolley, which will hereinafter be fully described and definitely indicated.

It comprises also a system of electric locomotion in which motor-propelled vehicles 55 running in opposite directions are supplied from the same conductors, the collectors being arranged to withdraw one contact from one conductor in passing.

In the accompanying drawings, illustrating 60 my invention, Figure 1 is a side elevation of my trolley. Fig. 2 is a plan view. Fig. 3 is a top plan view showing two trolleys in the act of passing one another. Fig. 4 is a side elevation of a system of electric locomotion 65 embodying my improvements, and Fig. 5 is a detail view showing one mode of supporting the supply-conductors.

In a system of locomotion of this kind it is evident that the earth cannot be used for any 70 part of the circuit, the contact of the wheels of the vehicle with the ground being so slight that very little current would flow even if the ground were wet. It is important also that switches at determinate points of the 75 road to permit trolleys to pass be dispensed with, since such devices not only greatly increase the expense of equipment, but introduce factors which interfere with reliable operation of the system and enforce delays in 80 the movements of vehicles, which are highly desirable to avoid. I avoid these uncertain and objectionable features by providing two continuous insulated conductors, each being appropriated by vehicles having one direction 85 of transit over the roadway, the other conductor being engaged by a yielding contact which automatically folds out of the way in passing another vehicle.

A simple form of construction for a trolley 90 embodying my improvements is shown in the drawings, though it will of course be understood that this construction may be varied so long as the generic features of novelty hereinafter pointed out in the claims are embodied.

1 in Fig. 4 represents a road-vehicle of any desired construction provided with an electric motor (symbolically represented at 2) and with two current-leading conductors 3 4, (see 100 Fig. 1,) connecting with metallic terminals 5 6, secured to the trolley. The trolley-frame

is composed of two stiff plates. (Seen in side elevation in Fig. 4, end elevation in Fig. 1, and plan at 78.) These are hinged together at 910. An ear 11 projects from a middle point of the plate 8 toward the plate 7, the latter being provided with a lug 12 to serve as an abutment for a screw-pin 13, having a squared end for the use of a key on a staff, permitting a motorman to tighten or loosen the trolley for connection or disconnection. The plates 78 when adjusted form the two limbs of a V and have secured at their upper ends stud-bolts forming journals for the trolley-wheels 14 15 14^a 15^a, having grooved peripheries meeting at the contiguous points to embrace the line conductor 16. Thus it will be seen that when the key-pin 13 is adjusted the trolley-wheels may be forced to a firm seat on the conductor. Two pairs of wheels are provided for each trolley, thus giving two points of support.

Secured to the plate 8 is a block of insulating material or an insulated plate of metal, as may be desired, (shown at 17,) in which is journaled an arm 18, carrying a long vertical axis 19, on which is journaled a light collecting-roller 20. The latter makes electric contact with the companion supply-conductor 16^a. It is desirable to have this arm and contact-roller as light as possible to prevent lateral pressure on the conductor 16^a, and to this end the arm may be made of sheet-steel and the roller of aluminium. A coil-spring 21 is preferably mounted around the axis of the arm 18, one end being fixed to the insulated block 17 and the other to the arm. Thus the arm is held against the conductor 16^a with a yielding or elastic pressure.

One terminal of the leading-in conductors 40 of the vehicle connects with a metal spur 22 of the trolley-frame and the other with an insulated plate 23, and from the latter a flexible conductor 24 connects with the folding arm 18. Firmly secured to the plate 8 at a point above the level of the arm 18 is a metallic guide-rail 25, mounted on two or more metallic posts secured to the trolley-frame. These rails are inclined at the leading end toward the conductor on which the trolley rolls. Thus when two trolleys are passing the collectors 20 are forced aside by the guide-rails, an uninterrupted completion of the circuit being maintained, as the two trolleys pass one another, with ease. The supply-conductors 55 may be mounted on supporting-posts in any desired way. They should be firmly set against lateral motion on the posts. One form of construction is indicated in Fig. 5, in which 26 26^a are metallic rods securely mounted on insulating-chairs seated on a supporting-arm of a line-post 27. At the foot of the rods are metallic webs brazed to the line conductor, so as to form a stiff connection. The arm 18 is free to obey its controlling-spring, and thus hugs the conductor with which it is to make contact notwithstanding any lack of alignment of the latter with relation to its com-

panion conductor at points intermediate the supports.

It will be noted that the connection between the motor-vehicle and the trolley is flexible. Thus the trolley trails after the vehicle, being drawn along by the latter.

Having thus described my invention, what I claim as new, and desire to secure by Letters Patent, is—

1. A system of electric locomotion comprising two line conductors, electrically-propelled vehicles connecting therewith, and current-collectors for the vehicles traveling upon and supported by one conductor and provided with a folding contact engaging the other conductor, said contact being adapted to be withdrawn to permit another collector to pass. 80

2. A system of electric locomotion comprising two line conductors, electrically-propelled vehicles connecting therewith, and current-collectors for the vehicles traveling upon and securely connected with one conductor, oppositely-moving collectors being connected 90 to opposite conductors, a folding, insulated, and elastically-yielding arm on each collector engaging the companion conductor and leading current therefrom, and guide-rails to automatically force aside the yielding contact-arms to permit two trolleys to pass. 95

3. A system of electric locomotion comprising two line conductors, electrically-propelled vehicles connecting therewith, and current-collectors for the vehicles traveling upon and securely connected with one conductor, oppositely-moving collectors being connected with opposite conductors, a folding, insulated, and elastically-yielding arm on each collector 100 engaging the companion conductor and leading current therefrom, and metallic guide-rails in electric connection with the collector-frame to force aside the yielding contact-arms 105 to permit the trolleys to pass and preserve electric connection with the line conductors. 110

4. A current-collector or trolley provided with means for supporting it on one conductor of a supply system and having an elastically-yielding arm carrying a contact to engage a companion conductor, and means for 115 guiding the arm of a similar trolley on the companion conductor around the first-mentioned trolley.

5. A current-collector or trolley provided with means for supporting it on one conductor of a supply system and having an elastically-yielding arm carrying a contact to engage a companion conductor, and means for guiding the arm of a similar trolley on the companion conductor around the first-mentioned 125 trolley while preserving the circuit practically unbroken.

6. A current-collector or trolley provided with means for supporting it on one conductor of a supply system, an elastically-yielding arm adapted to make contact with a companion conductor, and a guide-rail on the trolley-frame to force aside the arm of a trolley on the companion conductor thereby per-

mitting the trolleys to pass one another, substantially as set forth.

7. A current-collector or trolley mounted to roll on one conductor of a supply system, 5 an elastically-yielding arm adapted to make contact with the companion conductor, and a guide-rail on the trolley-frame to force aside the arm of a trolley on the companion conductor, thereby permitting the trolleys to pass

one another.

8. A current-collector or trolley provided with means for mechanically securing it to one conductor of a supply system, a yielding arm adapted to make contact with the companion conductor, and a guide-rail on the trolley-frame to force aside a similar yielding arm of a trolley on the companion conductor, thereby permitting the trolleys to pass one another.

20 9. A current-collector or trolley provided with grooved current-collecting rollers holding it in mechanical engagement with one conductor of an electric supply system, a yielding arm insulated from the rollers making contact with the companion conductor, and a guide-rail on the trolley-frame for deflecting a similar yielding arm on passing an oppositely-moving trolley rolling on the companion conductor.

25 10. A current-collector or trolley supported by one conductor of an electric supply system, a yielding insulated arm engaging the

companion conductor, and a metallic guide-rail secured to the trolley and electrically connected with the supporting-conductor and 35 adapted to engage the said yielding arm while two trolleys are passing one another, whereby the circuit through a motor-driven vehicle may be preserved without material interruption while two oppositely-moving trolleys are 40 passing one another.

11. A current-collector or trolley provided with grooved current-collecting rollers holding it in mechanical engagement with one conductor of an electric supply system, means 45 for locking or unlocking the rollers to the conductor, and an insulated contact adapted to engage the companion aerial conductor.

12. A current-collector or trolley provided with collecting-contacts mechanically locked in engagement with one conductor of an electric supply system, an insulated contact adapted to engage the companion aerial conductor, and a key accessible for operation from beneath for unlocking the trolley-contacts from the conductor to which they secure the trolley.

In testimony whereof I have hereunto subscribed my name this 11th day of November, A. D. 1896.
